UNITED STATES PATENT OFFICE.

JOHN A. GERMONPREZ, OF DETROIT, MICHIGAN, ASSIGNOR OF ONE-HALF TO WELLINGTON F. EVANS, OF DETROIT, MICHIGAN.

TAPPET CONSTRUCTION.

Application filed April 30, 1921. Serial No. 465,891.

To all whom it may concern:

Be it known that I, JOHN A. GERMONPREZ, a citizen of the United States of America, residing at Detroit, in the county of Wayne and State of Michigan, have invented certain new and useful Improvements in Tappet Constructions, of which the following is a specification, reference being had therein to the accompanying drawings.

10 In my companion application, Serial Number 434,487, filed January 3, 1921, I have disclosed a valve operating member wherein a hardened disk is seated within a recess in said member and held therein by its engagement with the portion of the member surrounding the recess, to form a smooth hardened contact surface adapted to be engaged by a valve operating cam, but it has been found that a third member may be employed with equal efficiency to hold the disk in place upon the operating member, and an object of this invention is to provide simple and efficient means other than that shown in my prior application for holding 25 the disk in place and which holding means is so constructed as to facilitate and cheapen manufacture.

A valve tappet or member which is operated by a cam in a valve operating mechanism, is commonly arranged to loosely engage and operate a valve lifting member, and it has been found that inefficient operation is sometimes occasioned by the wearing away and disintegration of the contact surface carried by the tappet which is brought into contact with the valve lifting member when the tappet is operated by the cam.

It is an object of this invention to provide simple and efficient means for preventing the wear and disintegration of this contact surface and thus obviate the necessity for hardening and grinding the tappet body or member carried thereby which is brought into contact with the valve lifting member 45 when the tappet is operated.

A further object is to provide a tappet with a separate hardened contact member at each end of the tappet, one to form a hardened contact surface to be engaged by the operating cam and the other to form a hardened contact surface to be engaged by the valve lifting member, said hardened members being held in firm contact throughout the faces in contact with the end of the 55 tappet with unyielding seats at both ends of

the tappet, said hardened members and tappet forming a rigid unyielding member of unvarying length forming a part of the valve operating mechanism.

With the above and other ends in view, 60 the invention consists in the matters herein-after set forth and more particularly pointed out in the appended claims, reference being had to the accompanying drawing in which—

Figure 1 is a side elevation of a tappet illustrative of an embodiment of the invention and showing parts broken away and in section;

Fig. 2 is an elevation of the lower end 70 portion or head of the tappet shown in Fig. 1 and illustrating a slightly modified construction, parts being broken away and in section to more clearly show the construction;

Fig. 3 is an elevation of an upper end portion of the tappet illustrating a further modification of the construction shown in Fig. 1 and showing parts broken away and in section;

Fig. 4 is a side elevation of another common form of tappet wherein the same is provided with adjusting means and a construction illustrative of the invention is applied to such tappet adjusting means, portions of 85 the adjustment member and head being broken away and in section to more clearly disclose the construction, and

Fig. 5 is a detail showing the adjusting member of the tappet illustrated in Fig. 4, 90 in elevation and of slightly modified construction, with portions broken away and in section.

As shown in Fig. 1 of the drawing, the tappet comprises a body or stem 1 which is formed with the usual head 2 at one end and this head is faced off at its lower side to provide a seating surface for a hardened disk 3, which disk is held in place and in firm seating contact throughout the entire inner face with the end surface of the head, by a holding ring or band 4. This holding ring has an inwardly inclined upper edge portion 5 to engage a correspondingly inclined peripheral edge of the head and is also formed with an inclined edge portion 6 along its lower edge to engage an inclined or beveled peripheral edge of the hardened disk 3.

In the manufacture of these tappets, by 110

means of a suitable press and dies, the disk is forced into firm seating contact throughout the entire inner face, with the end surface of the head and the holding ring is simultaneously forced into firm contact with the head and its edge portions or flanges 5 and 6 bent inwardly and formed down firmly upon the inclined peripheral edges of the head and disk. The hardened disk 10 which forms the hardened contact surface for the head to be engaged by an operating cam of a valve operating mechanism, is thus firmly seated and held in place upon the tappet head by means of a third member or ring 4 which may be very cheaply and quickly applied by the same machine and during the same operation which seats the disk upon the head in the manufacture of the tappet.

20 In the modified construction shown in Fig. 2, the head 2 is formed with a peripheral groove 7 to receive the upper flange 5 of the holding ring 4 so that the upper inclined surface of the head will be a smooth, flush surface, giving a neat appearance and providing a better hold for the ring upon the head.

25 In Fig. 1 the upper end of the body or stem 1 of the tappet is formed with a recess 30 8 to receive a hardened disk 9 adapted to form a hardened end contact surface for the tappet, and this disk is firmly held in its recess by bending inwardly the upstanding edge portion or flange 10 on the body 1 which surrounds the recess, said flange being forced into firm engagement with the beveled peripheral edge 11 of the disk.

35 The hardened disk is thus firmly held in the recess of the end of the body and in firm seating contact throughout the entire inner face with the bottom of this recess, by the inbending of the peripheral flange 10 which is formed by the recessing of the end of the body. The body is therefore 40 provided with a very hard wear surface without the necessity for hardening and grinding the end of the body, which hardening process is difficult to perform with a certainty of securing the exact hardness desired so that it will not be so hard as to 45 be liable to crack in use and will not be so soft as to cause wear in operation. Where the body is hardened, it is necessary to grind it after the hardening operation and 50 thus the cost of manufacture is increased. By recessing the end of the body and setting a hardened disk into this recess, grinding of the body is obviated and a contact surface provided which will be of the desired hardness to withstand the wear, and 55 as this disk is in firm contact with the bottom of the recess throughout the entire area of the inner face of the disk, said disk in effect becomes an integral part of the 60 body and liability of its becoming loosened

under operating conditions and broken by the hammering action of the member contacting therewith, is obviated.

65 In the construction just described which is substantially the same as that disclosed in the companion application previously mentioned, a very heavy pressure is necessary to force the peripheral flange 10 into firm contact with the hardened disk and it is extremely difficult to avoid causing flexure of the thin disk. In the companion application the flexure thus produced is desirable and accomplishes a useful function, but where it is desired to secure a flat plate upon a flat seat, flexure of the thin plate would leave an undesirable space between the inner surface of the plate and the end of the tappet body. Annular rings of the form illustrated in all of the figures 70 75 80 85 90 95 100 105 110 115 120 125 130 of the form illustrated in all of the figures may be used to hold a flat disk firmly in contact with a flat seat without producing flexure of the disk. The annular holding ring of steel placed upon the oppositely beveled surfaces of the peripheries of the tappet and of the plate, exerts a wedging action which maintains a permanent firm engagement of the abutting surfaces.

The common form of tappet shown in Fig. 4 comprises a body 1 and an adjustable member carried by the upper end of the body, said member consisting of a screw-threaded stem 12 which is screwed into a longitudinal axial opening in the upper end of the body 1, and a head 13 on said stem, a lock nut 14 being provided on the stem to engage the end of the body and hold the adjustable member in the position to which it is adjusted to change the over-all length of the tappet. The upper contact 105 end of the tappet, which in this construction is the end face of the head 13, is formed by a hardened disk which is secured in a recess in the end of the head in the same manner and by the same means as said disk 9 shown in Fig. 1 is held in place.

A modified construction of adjustable tappet member is shown in Fig. 5, the head 13 being formed with a projecting end portion 15 which is faced off to provide a seating surface for the hardened disk 16, and this disk is secured in firm contact with its seat by a securing ring 17 similar to the ring 4 and which ring has edge portions 18 and 19 formed down upon the beveled edge of the disk and a similar undercut annular bevel on the head, the construction and method of applying the ring being substantially the same as in the securing of the disk 3 to the head 2 of the tappet.

In Fig. 3 a modification of the means for and method of securing the disk 9 directly to the end of the tappet body, is shown. In this modified construction, the tappet body is formed with a projecting

end portion 20 similar to the portion 15 of the head 13, and the hardened disk 21 is secured upon the flat end surface of this portion by means of a securing ring 22 5 similar to the ring 17 and which is formed and applied in a like manner.

Obviously the form and construction of the several parts may be further varied within the scope of the appended claims 10 without departing from the spirit of the invention and I do not therefore limit myself to the particular construction shown.

Having thus fully described my invention, what I claim is:—

15 1. As a new article of manufacture, a tappet comprising a member having a flat end surface, a disk of thin hardened steel seated upon said surface and un-stressed, and a separate annular securing member 20 having an edge portion formed inwardly over a peripheral edge portion of said disk,

and an edge portion formed inwardly upon a peripheral edge portion of said member whereby said edge portions of the securing member are stressed to hold said disk 25 firmly seated upon said end surface of said member without stressing the disk.

2. As a new article of manufacture, a tappet comprising a member having a flat end surface and a peripheral beveled edge, 30 a disk of thin hardened steel seated upon said surface and formed with a beveled edge, the beveled edge portions of said member and disk being inclined inwardly, and a separate annular securing member having edge portions formed inwardly against said beveled surfaces of said member and disk with said edge portions stressed to firmly contact said surfaces.

In testimony whereof I affix my signature. 40

JOHN A. GERMONPREZ.
